MILLARD SUMTER BLACK AND FREDERICK M. BRAMBLEY, OF BREA, CALIFORNIA.

PACKING OVERSHOT.

Application filed December 18, 1922. Serial No. 607,705.

To all whom it may concern:

Be it known that we, MILLARD SUMTER BLACK and FREDERICK M. BRAMBLEY, each a citizen of the United States, and residents 5 of the city of Brea, county of Orange, and State of California, have invented new and useful Improvements in Packing Overshots, of which the following is a full, clear, and accurate disclosure.

10 This invention relates to a tool, and more particularly to a packing overshot, and it is an object of this invention to provide a tool of this character which is simple, effective and practical.

15 With various well drilling methods, and particularly with the rotary drilling method, liquid is circulated—usually upwardly around the drill pipe—in the hole to carry out the cut material and to keep the hole 20 clear. The desired circulation of liquid is usually maintained by pumping the liquid through the drill pipe which operates the drilling tool. When the drill pipe breaks, as it occasionally does, it is, of course, necessary to catch the broken off part with a suitable tool and remove it from the well, and it is desirable, and, in many cases imperative, that the circulation of liquid, which, of course, is lost when the drill pipe breaks, 25 be restored without too much delay.

30 Tools known as overshots, have been developed for the purpose of catching the broken-off portions of a string of drill pipe, and packing means have been embodied in overshots for the purpose of packing the connection between the overshot and broken-off section of drill pipe so that the desired circulation of liquid can be reestablished as soon as the broken-off section of drill pipe 35 has been caught by the overshot. Packing overshots, or overshots equipped with packing means, such as have been heretofore provided, have been more or less unsatisfactory or unreliable for various reasons.

40 In practice we have found that packing overshots heretofore proposed are of such arrangement and construction that they are cumbersome and take up considerable space for their operation, that they do not, in 45 many cases, form an effective connection between the overshot and broken-off section of pipe, and that they are not sufficiently effective and reliable to be of any great commercial value.

50 It is an object of the present invention

to provide a packing overshot which is compact, and of such arrangement and configuration that it will operate properly and effectively in a comparatively small space, and, therefore, is applicable for use in many 60 situations where such devices have heretofore been inoperative.

Another object of our invention is to provide a packing overshot in which the packing means cooperates with a coupling of the 65 broken-off string of the drill pipe, and not with the pipe proper, and, therefore, does not have to be actuated very far from its normal position in order to make the desired connection between the overshot and 70 the broken-off string of drill pipe.

Another object of our invention is to provide a packing overshot in which the packing means operates to effectively seal the overshot and broken-off string of drill 75 pipe before the overshot lifts the broken-off string of drill pipe, but which is not and cannot be further actuated by operation of the overshot to lift the broken-off string of drill pipe. By carrying out this object of 80 our invention we provide a tool in which the packing is operated only sufficiently to make the necessary connection between the overshot and broken-off string of drill pipe, and in which the overshot operates to lift 85 the broken-off string of drill pipe independently of the packing means so that the packing means is not forced or put under undue strain when the overshot is operating to lift or hold the broken-off string of drill pipe. 90

Another object of our invention is to provide a packing overshot in which the packing operating means has a definite limited range of operation, so that the packing means is only operated within the proper 95 limits.

The various objects and features of our invention will be best and more fully understood from the following detailed description of a typical preferred form of our invention, throughout which reference is had to the accompanying drawings, while the scope of our invention will be particularly pointed out in the appended claims. In the 100 drawings:

Fig. 1 is a vertical detail sectional view of a packing overshot, embodying the present invention, showing the various parts in their normal unactuated position;

Fig. 2 is a view similar to Fig. 1, showing 110

a string of drill pipe in connection with the tool, and showing the tool in position on the drill pipe where it is sealed to the drill pipe by the packing means and is gripping the drill pipe to lift it upon upward movement;

Fig. 3 is a detail transverse sectional view of the tool, being a view taken as indicated by line 3—3 on Fig. 1;

10 Fig. 4 is a detail transverse sectional view of the tool, taken as indicated by line 4—4 on Fig. 1; and

15 Fig. 5 is a detail transverse sectional view of the tool, taken as indicated by line 5—5 of Fig. 1.

The tool provided by our invention comprises, generally, a body 10; means 11, carried by the body 10 to grip or engage a string of drill pipe, or the like, to lift it upon upward movement of the body; packing means 12, arranged within the body and adapted to be actuated to engage a drill pipe arranged through the body to form a fluid-tight seal between the body and drill pipe; 25 and operating means 13 for the packing means 12 adapted to be actuated by certain manipulation of the tool relative to a drill pipe to actuate the packing means 12 in the manner just specified. In Fig. 2 of the drawings, we show the tool in combination with a typical string of drill pipe 14 which comprises a plurality of pipe sections 15 connected by suitable couplings 16.

The body 10 of the tool provided by our invention is preferably a unitary tubular member, internally screw threaded at its upper end so that it can be conveniently mounted on the lower end of a string of pipe or casing or on a suitable coupling device 40. 17 mounted on the lower end of a string of pipe or casing, and externally screw threaded at its lower end so that a suitable guide shoe 18, or the like, can be conveniently mounted on it. The exterior of the body 10 is preferably smooth and uniform in size throughout the length of the body, as we have illustrated in the drawings. An upwardly facing shoulder 19 is formed in the body 10 near its lower end, and an annular 45 projection or flange 20 extends from the inner wall 21 of the body at a point spaced considerably above the shoulder 19. Above the flange 20 the inner wall 21 of the body is preferably bored or otherwise finished, 50 so that it is uniform in size and is smooth.

The means 11, which we have illustrated in the drawings for engaging the string 14 of drill pipe so that it is lifted upon upward movement of the body, includes a plurality of resilient fingers 22. In the particular tool illustrated in the drawings, there are four fingers 22 arranged symmetrically in the body 10, and secured to the body 10, as by suitable rivets 23, so that their lower 65 ends seat on the shoulder 19 while their

upper portions extend freely upwardly and inwardly through the body so that their upper ends are spaced a considerable distance inwardly from the inner wall 21 of the body. The fingers 22 are made resilient and are proportioned so that they can be depressed or forced outwardly until they lie close to the inner wall 21 of the body 10. This particular means 11 is the general type commonly used in overshots, and is herein illustrated as a typical means which may be employed in carrying out our invention. The operation of the means 11 will be obvious to those familiar with the art. As the body 10 passes downwardly over a string of drill pipe, or the like, the fingers 22 are depressed by their passage over the couplings 16 and bear closely on the sections of pipe 15 so that they will engage under a coupling 16 when the tool is moved upwardly to connect the tool and string of drill pipe so that the drill pipe will be carried up with the tool.

The packing means 12, which we have illustrated in the drawings, includes an annular body 24 of expansible packing, for instance, rubber, a lower ring 25 arranged at the lower end of the body of packing, and an upper ring 26 arranged at the upper end of the body of packing. In accordance with our invention the packing means 12 is supported in the body 10 by the flange 20 which is located immediately above the upper ends of the fingers 22. The packing means is arranged in the body 10 through the upper end thereof so that the lower ring 25 seats on the flange 20. We provide the packing means 12 with the lower ring 25 so that the lower end of the body of packing 24 will be completely supported and will not be forced into the notches 27 provided in the flange 20, as hereinafter described. We form the rings 25 and 26 with recesses 28, which receive flanges 29 provided on the ends of the body of packing to hold the body of packing in the rings. The upper ring 26 is slidably carried in the body 10 and is adapted to be moved downwardly to actuate or compress the body 24 of packing so that it expands inwardly to engage a coupling 16 and thereby sealing the body 10 with a string of drill pipe. In the particular form of construction illustrated in the drawings, the ring 26 is retained in the body 10 by the coupling device 17 which screw threads into the upper end of the body.

The operating means 13, provided by the present invention for actuating the packing means, includes arms 30 connected with the upper ring 26 of the packing means and arranged to extend downwardly to a point below the upper end of the fingers 22, and fingers 31 carried by the lower end portions of the arms 30. The arms 30 are preferably

flat straplike members, riveted, or otherwise suitably secured, to the ring 26 of the packing means so that they extend downwardly through suitable openings 32 cast, or otherwise suitably formed, in the packing means. Notches or recesses 27 are provided in the flange 20 to pass and more or less guide the arms 30. We prefer to arrange the arms 30 through the body of packing, rather than 5 back of the body of packing so that the packing seats against the inner wall 21 of the body completely around the body. The fingers 31 are resilient members having their lower portions riveted, or otherwise suitably secured, to the lower end portions of the arms 30 and having their upper portions extending freely upwardly and inwardly through the body so that their upper ends are normally spaced somewhat above the upper 10 ends of the fingers 22 and are spaced inwardly from the inner wall of the body. The fingers 31 are adapted to operate in a manner more or less similar to the fingers 22. When the tool is being passed downwardly over a string of drill pipe the fingers 31 will be depressed or forced inwardly by the couplings 16 and will bear closely against the sections 15 of the pipe so that they will engage under a coupling upon the 15 tool being moved upwardly. In the particular tool illustrated in the drawings, we have shown four arms 30 and fingers 31, arranged symmetrically in the body so that they come between the fingers 22. 20

30 In operating the tool it is lowered over the string 14 of drill pipe which is to be lifted until the fingers 22 and 31 have completely passed over at least one coupling 16. The body 10 is then moved upwardly causing the fingers 31 to engage under a collar 16 so that they are held by the collar and in turn hold the upper ring 26 of the packing means and the body is moved on upwardly until the fingers 22 engage under the collar 25 16. While the ring 26 is being held and the body moved upwardly the body of packing 24 is, of course, compressed between the ring 26 and flange 20 so that it expands inwardly and engages the coupling 16, as we have 30 clearly illustrated in Fig. 2. When the fingers 22 engage under the coupling 16 further upward movement of the body will not further actuate the packing means to further expand the body of packing, but will cause the string 14 of drill pipe to be carried along with the tool and will cause the packing means to be maintained in the actuated condition so that the body is effectively sealed to the coupling 16. It will be obvious, of course, that fluid forced down through the string of pipe or casing carrying the tool will pass through the string of drill pipe held by the tool rather than out between the tool and the string of drill pipe. 35

40 It is to be particularly noted that the tool provided by my invention is extremely simple in its construction and operation, that it is particularly compact so that it can be passed through a hole only slightly larger in diameter than the couplings 16 of the string 14 of drill pipe, that the parts are so related that the packing means cooperates with a coupling rather than a section of pipe, and, therefore, the body of packing needs to be expanded only slightly inwardly 45 to engage the string of drill pipe, and that the packing means is actuated only a predetermined amount and cannot by any possibility be actuated beyond that amount no matter how much strain is put upon the tool. It is to be understood that the tool may be used to handle objects other than drill pipe, so therefore we mean the term drill pipe, or, drill pipe including sections joined by couplings to include any other objects that may be handled by the tool. 50

Having described only a typical preferred embodiment of our invention we do not wish to limit ourselves to the particular details hereinabove set forth, but wish to reserve to ourselves any changes or variations that may appear to those skilled in the art or that may fall within the scope of the following claims. 55

Having described a preferred form of our invention, we claim:

1. A tool of the character described adapted to operate on a string of pipe including sections joined by couplings which includes, a body adapted to pass over the string of pipe, means carried by the body and adapted to cooperate with a coupling of the string of pipe to make a connection between the body and the string of pipe, whereby the string of pipe is moved with the body, and packing positioned with reference to said means to engage a coupling of the string of pipe to pack the body with the string of pipe. 60
2. A tool of the character described adapted to operate on a string of pipe including sections joined by couplings which includes, a body adapted to pass over the string of pipe, means carried by the body and adapted to cooperate with a coupling to make a connection between the body and the string of pipe whereby the string of pipe is moved with the body, and packing arranged in the body to engage said coupling to pack the body with the string of pipe. 65
3. A tool of the character described adapted to operate on a string of pipe including sections joined by couplings which includes, a body adapted to pass over a string of pipe, means carried by the body and adapted to cooperate with a coupling to make a connection between the body and the string of pipe whereby the string of pipe is moved with the body, and packing means independent of said first mentioned means 70

and adapted to cooperate with said coupling to pack the body with the string of pipe.

4. A tool of the character described including, a body adapted to pass over a pipe, means carried by the body for connecting the body with the pipe, packing carried by the body, and means operable independently of said first mentioned means for operating the packing so that it packs the body with the pipe.

5. A tool of the character described including a body adapted to pass over a pipe, packing carried by the body operable to engage the pipe, and two parts carried by the body and related to successively cooperatively engage the pipe upon upward movement of the body relative to the pipe, the first part to cooperatively engage the pipe operating the packing and the other part connecting the pipe and body so that they move together.

6. A tool of the character described including, a tubular body adapted to pass over a pipe, means carried by the body to connect it with the pipe upon its being raised, packing carried by the body, operating means for the packing operable independent of said other means to actuate the packing upon raising of the body so that the body is packed with the pipe, and means limiting the range of operation of the operating means.

7. A tool of the character described adapted to operate on a string of pipe including sections joined by couplings which includes, a body adapted to pass over the string of pipe, and means operative by upward movement of the pipe to pack the body with the pipe at a coupling and thereafter connect the body with the pipe so that it is moved with the body, said means including two independently operable members adapted to cooperate with a coupling one after the other.

45 8. A tool of the character described adapted to operate on a string of pipe including sections joined by couplings which includes, a body adapted to pass over the string of pipe, means carried by the body and adapted to cooperate with a coupling to make a connection between the body and the string of pipe whereby the string of pipe is moved with the body, and packing means arranged in the body to cooperate with said coupling to pack the body with the string of pipe, said packing means including packing arranged to engage with the coupling and a resilient member for operating the packing and arranged to cooperatively engage the coupling.

9. A tool of the character described adapted to operate on a string of pipe including sections joined by couplings which includes, a tubular body adapted to pass over the string of pipe, means carried by

the body to connect the body with the pipe, packing carried by the body to be at a coupling when the body is connected with the pipe, and operating means for the packing including a resilient member adapted to cooperate with a coupling.

10. A tool of the character described adapted to operate on a string of pipe including sections joined by couplings which includes, a tubular body adapted to pass over the pipe, means carried in the body and adapted to cooperate with a coupling to connect the body with the pipe, packing carried in the body above said means so that it is at the coupling cooperating with said means, and operating means for the packing including a resilient member connected with the packing and arranged to cooperate with the coupling with which said first mentioned means cooperates.

11. A tool of the character described adapted to operate on a string of pipe including sections joined by couplings which includes, a tubular body adapted to pass over the pipe, means carried in the body and adapted to cooperate with a coupling to connect the body with the pipe, packing carried in the body above said means so that it is at the coupling cooperating with said means, and operating means for the packing including an arm extending downwardly from the packing and a finger extending upwardly from the lower part of the arm to cooperate with the coupling with which the first mentioned means cooperates.

12. A tool of the character described adapted to operate on a string of pipe including sections joined by coupling which includes, a tubular body adapted to pass over the pipe, a projection in the body, a resilient member secured in the body below the projection so that it extends freely upwardly and inwardly in the body, a body of packing carried on the projection, a ring slidably carried in the body above the packing, an arm secured to the ring and arranged to extend downwardly through the packing and past the projection, and a resilient finger secured to the lower part of the arm to extend freely upwardly and inwardly in the body so that its upper end is normally above the upper end of said member.

13. A tool of the character described including, a body adapted to pass over a pipe, packing means carried by the body and adapted to be actuated to engage the pipe by movement of the body in one direction, and a member carried by the body to engage and move the pipe when the body is moved in said direction and to limit the operation of the packing means.

14. A tool of the character described including, a body adapted to pass over a pipe, packing carried by the body, and two members adapted to engage the pipe, one con-

nected to the body and adapted to move the pipe and the other connected with the packing to actuate it.

15. A tool of the character described adapted to operate on a pipe, including sections joined by couplings, embodying a body adapted to pass over the pipe, two spring fingers in the body related to engage a single coupling, one connected to the body and 10 adapted to move the pipe and the other connected with the packing to actuate it.

16. A tool of the character described adapted to operate on a string of pipe including a body, packing carried in the body, 15 and operating means for the packing having a pipe engaging member at a point below the packing.

17. A tool of the character described adapted to operate on a string of pipe including, a body adapted to pass over the pipe, packing carried in the body, and means 20 for operating the packing including an arm extending downwardly from the packing and a spring finger extending upwardly 25 from the lower portion of the arm to engage the pipe.

18. A tool of the character described adapted to operate on a string of pipe, including a tubular body adapted to pass over 30 the pipe, an annular packing in the body

between two members, the upper one being movable, an arm extending downwardly from the upper member to a joint below the packing, and a spring finger extending upwardly from the lower portion of the arm 35 to engage the pipe.

19. In a device of the character described a tubular body, an annular packing carried in the body, a movable ring at the upper end of the packing, means for operating the 40 ring to expand the packing including a member extending downwardly from the ring to a point below the packing and a finger in connection with the member below the packing.

20. In a device of the character described a tubular body, an annular packing carried in the body, a movable ring at the upper end of the packing, means for operating the 45 ring to expand the packing including a member extending downwardly through the packing to a point below the packing and a finger extending upwardly from the lower end of said member.

In witness that we claim the foregoing we 50 have hereunto subscribed our name this 1st day of December, 1922.

M. SUMTER BLACK.
FREDERICK M. BRAMBLEY.
